Patented Feb. 11, 1919.

UNITED STATES PATENT OFFICE.

LEON GOLDMERSTEIN, (NOW BY JUDICIAL CHANGE OF NAME LEON CAMMEN,) OF NEW YORK, N. Y.

AEROPLANE.

1,294,083.

Specification of Letters Patent. Patented Feb. 11, 1919.

Application filed December 7, 1916. Serial No. 135,551.

To all whom it may concern:

Be it known that I, LEON GOLDMERSTEIN, a subject of the Czar of Russia, and resident of the borough of Manhattan, in the city, county, and State of New York, have invented certain new and useful Improvements 5 in Aeroplanes, of which the following is a specification.

This invention relates to means for silencing the exhaust of aeroplane engines.

Taking into consideration the fact that the rear portion of an aeroplane fuselage offers an unused space suitable for the expansion of exhaust gases, my invention 15 contemplates the novel utilization of such space as a muffler, by placing it in communication with the exhaust manifold of a forwardly installed motor.

In the drawing:—

20 Figure 1 is a plan view of an aeroplane having my improvements, and

Fig. 2 is an enlarged detail view of the exhaust muffling means.

The drawing shows a conventional form 25 of aeroplane, having supporting surface 1 and fuselage 2. The forward portion of the fuselage may contain the motor 3, and the rear portion of the fuselage, which is inclosed behind the cockpit 3^a, may afford the 30 space to which the engine exhaust is conducted, as by exhaust pipe 4.

The rearward inclosed portion of the fuselage, which may contain a muffler as 5, by reason of its dimensions, permits the expansion 35 of the exhaust gases therein prior to

their efflux from said chamber to the atmosphere.

While not restricted to any particular means of exit from the expansion chamber, I have shown an outlet 15 leading from said 40 chamber to the atmosphere. A baffle 14 may also be employed to direct said exhaust gases to said outlet 15.

I claim:—

1. In an aeroplane, in combination, a fuselage, an engine located in the forward portion thereof, a chamber entirely inclosed within the rearward portion of said fuselage, and means for conducting the exhaust products from said engine to said chamber. 45

2. In an aeroplane, in combination, a fuselage, an engine located in the forward portion thereof, a muffler entirely inclosed within the rearward portion of said fuselage, and means for conducting exhaust products from 50 said engine to said muffler.

3. In an aeroplane, in combination, a fuselage, an engine located therein near its forward end, a muffler chamber entirely inclosed within said fuselage, an intermediate 60 cockpit, and means for conducting exhaust products from said engine to said muffler chamber.

Signed at the borough of Manhattan, in the city, county, and State of New York, 65 this 6th day of December, A. D. 1916.

LEON GOLDMERSTEIN.
